CLAIM

The ornamental design for an electronic sealer for container, as shown and described.

DESCRIPTION

FIG. 1 is a top, front, right side perspective view of an electronic sealer for container, showing our new design; FIG. 2 is a bottom, rear, left side perspective view thereof; FIG. 3 is a front elevation view thereof; FIG. 4 is a rear elevation view thereof; FIG. 5 is a left side elevation view thereof; FIG. 6 is a right side elevation view thereof; FIG. 7 is a top plan view thereof; FIG. 8 is a bottom plan view thereof; and,

FIG. 9 is a top, front, right side perspective view of the electronic sealer for container of FIG. 1, shown at a reduced scale and in a condition of use.

The broken lines in the drawings depict portions of the electronic sealer for container that form no part of the claimed design. The broken lines showing the container in FIG. 9 depict environmental subject matter that forms no part of the claimed design.
